(57) **CLAIM**

The ornamental design for a display screen with graphical user interface for managing firm billing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface for managing firm billing showing one embodiment of our new design;

FIG. 2 is a front view of a second embodiment thereof; FIG. 3 is a front view of a third embodiment thereof; and, FIG. 4 is a front view of a fourth embodiment thereof.

The broken line showing of a display screen and portions of the graphical user interface form no part of the claimed design.
